(57) CLAIM

The ornamental design for a bag, as shown and described.

DESCRIPTION

FIG. 1 is a perspective view of a bag showing my new design;

FIG. 2 is a front elevational view thereof;

FIG. 3 is a rear elevational view thereof;

FIG. 4 is a left view thereof;

FIG. 5 is a right view thereof;

FIG. 6 is a top plan view thereof;

FIG. 7 is a bottom plan view thereof;

FIG. 8 is an enlarged view of portion labeled as 8 on FIG. 1;

FIG. 9 is an enlarged view of portion labeled as 9 on FIG. 1; and,

FIG. 10 is an enlarged view of portion labeled as 10 on FIG. 1.

The dash broken lines illustrate portions of the bag that form no part of the claimed design. The dot-dash broken lines encircling portions of the bag in FIG. 1 and the enlarged views in FIGS. 8, 9, and 10 form no part of the claimed design.

1 Claim, 10 Drawing Sheets
